UNITED STATES PATENT OFFICE.

HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

SHOE-SEWING MACHINE.

1,158,771.

Specification of Letters Patent.

Patented Nov. 2, 1915.

Application filed March 24, 1911. Serial No. 616,562.

To all whom it may concern:

Be it known that I, HARRIE A. BALLARD, of Boston, in the county of Suffolk and State of Massachusetts, have invented certain new and useful Improvements in Shoe-Sewing Machines, of which the following is a specification.

This invention relates to shoe-sewing machines, and its purpose is to provide instrumentalities for improving the step-by-step feeding operation and for holding the work securely during the intervals between the feeding steps.

The invention is illustrated in connection with a chain-stitch machine, and the various instrumentalities in which the invention is embodied are especially adapted to so-called "turned" work, but they may also be used when attaching welts to so-called "welt" shoes.

Of the accompanying drawings which represent one adaptation of the invention: Figure 1 represents the group of instrumentalities which act upon the work to feed the same and to form the stitches. Fig. 2 represents two coactive work-engaging members, one of which engages the inner side of the between substance, and the other of which engages the outer side thereof to clamp and feed the work. Fig. 3 represents the member which engages the inner side of the between substance, and a member which engages the outer side of the between substance to hold the work stationary during the intervals between the feeding steps. Fig. 4 represents the group of instrumentalities shown by Fig. 1, in different positions. Fig. 5 represents the members shown by Fig. 2, with the needle in the work. Fig. 6 represents one of the members, included in Fig. 3, for holding the work stationary. Fig. 7 represents a horizontal section of a portion of a shoe-sewing machine, the instrumentalities which engage the outer side of the work being shown in plan. Fig. 8 represents a vertical section indicated by the line 8—8 of Fig. 7. Fig. 9 represents a side elevation of the two instrumentalities which engage the outer side of the between substance. Fig. 10 represents a side elevation, partly in section, of a chain-stitch shoe-sewing machine provided with the instrumentalities illustrated by the preceding figures. Fig. 11 represents a reverse side elevation of the machine shown by Fig. 10.

Fig. 12 represents a side elevation of the two members which engage the outer side of the between substance, and the member which engages the inner side thereof. Fig. 13 represents a front elevation of a laterally movable feed carriage and its operating mechanism. Fig. 14 represents a front elevation of the group of instrumentalities which act upon the work. Fig. 15 represents an elevation of a swinging member provided with gear teeth for engaging the needle holder, and with a cam for actuating the channel guide. Fig. 16 represents a rear vertical section of mechanism for locking the work rest and the auxiliary work rest. Fig. 17 represents a section on line 17—17 of Fig. 16. Fig. 18 represents an elevation of devices for expanding the split ring shown in Fig. 17. Fig. 19 represents a lever for actuating the devices shown in Fig. 18. Fig. 20 represents a movable hanger for the lever shown by Fig. 19. Fig. 21 represents an elevation of devices by which the main work rest is locked. Fig. 22 represents a section on line 22—22 of Fig. 21, including additional elements. Fig. 23 represents a vertical transverse section through the needle and channel-guide mechanism, the plane of the section intersecting the axis of the needle holder, viewed from rear to front.

The same reference characters indicate the same parts wherever they occur.

The machine to which the present invention is adapted is provided with a curved, hooked needle 10 which, being arranged for sewing welts and turned work, enters the between substance of the boot or shoe from the outer side and emerges from a channel formed in the sole. A sole is indicated at 11, and a last at 12. The sole is channeled at 13 to form a flap 14. The outer edge of the sole is rabbeted to form a shoulder 15 and a feather 16. When the work is in position for sewing, it is arranged so that the needle will enter the between substance in the angle formed by the shoulder 15 and feather 16.

The member 17, which is adapted to enter the channel 13 and engage the inner side of the between substance, is usually termed a channel guide or opener. It raises the flap 14, braces the between substance against the forward thrust of the needle, coacts with the member 18 to clamp the between substance, and moves laterally with the member 18.

while gripping the between substance, to feed the work.

The member 18 is arranged to engage the outer side of the between substance. This member (see Fig. 14) is oppositely disposed to the member 17 and is movable laterally in unison with the member 17 for feeding the work. The members 17 and 18 have relative movement toward and from each other so that they may clamp the between substance prior to their feeding movement and may release the between substance prior to moving laterally in the opposite direction. The member 18 has two separated fingers, indicated respectively at 18^a and 18^b.

The finger 18^b is arranged to engage the stitch-receiving flange, and the offset portion of the upper or welt as the case may be and the finger 18^a engages only said offset portion. The flange and offset portion just mentioned lie respectively against the shoulder 15 and feather 16 of the insole, according to well-known construction. The fingers 18^a and 18^b, in addition to feeding the work, brace the between substance against the backward and upward pull of the needle and thread, by their engagement with said stitch-receiving flange and offset portion. Said flange and offset portion are thus held so that the needle and thread cannot pull them away from the shoulder 15 and feather 16 of the insole. The finger 18^b engages the work in advance of the needle and the finger 18^a engages the stitched portion of the work, sufficient space being provided between the fingers for the needle and thread.

The back rest, sometimes termed a bunter, is indicated at 19. An auxiliary back rest 40 is provided in the form of a pointed work-engaging member 20 which is mounted in a holder 21. The member 20 has a series of points (Fig. 7) which coact with the stitch-receiving flange of the upper on the line of 45 the stitches but in advance of the stitches. This member has a relatively broad under surface which bears upon the offset portion of the upper which connects the stitch-receiving flange with the body of the upper 50 and which presses said offset portion against the feather 16 of the insole. This member 20 tucks the pulled-over portion of the upper into the angle formed by the feather 16 and shoulder 15 of the insole, and the upper is thus formed-in, as it were, in 55 advance of the stitches. In addition to serving as a forming-in tool, the member 20 serves to hold the work stationary while the feeding elements 17 and 18 are disengaged 60 from the work and moving back for a fresh hold upon the work. The holder 21 is mounted so as to be movable toward and from the work and is provided with operating mechanism whereby the pointed member is retracted prior to the beginning of the

feed stroke of the feeding elements, and is advanced into operative engagement at the end of the feed stroke and before the return stroke of the feeding elements.

The bunter 19 is, as usual, arranged to be 70 engaged by the shoe upper and is provided with spring-tension means for advancing it toward the work and with means for locking it and releasing it at the desired times.

In the machine illustrated, the needle, as 75 well as the members 17 and 18, is laterally movable and is operated to feed the work in conjunction with the members 17 and 18. The invention, however, is not limited to machines in which the needle is moved to 80 feed the work, because the members 17 and 18 are adapted to feed the work without any assistance from the needle. In this form of machine the members 17 and 18 and the needle are all mounted upon a laterally 85 movable carriage so that they move laterally in unison.

The needle is affixed in a holder 22, and the holder is pivotally mounted upon a stud 23 in a carriage 24. The carriage is laterally movable in guides 25 on the frame of the machine. (See Figs. 10 and 13). The carriage is reciprocated by a lever 26 and cam 27, the cam being mounted upon a main power shaft 28, and the lever having a roll 29 co-operating with the cam. The lever is mounted upon a fulcrum stud 30 and is connected with the carriage by a stud 31. The lever and carriage are slotted as indicated at 32 and 33 so that the stud 31 may be adjusted to vary the length of stroke imparted to the carriage. This mechanism and the greater part of the mechanism hereinafter described is similar to that illustrated and described in U. S. Letters Patent 1,125,038, 105 granted January 19, 1915.

The needle holder 22 is provided with gear teeth 34 which are engaged by gear teeth 35 (see Fig. 11) on a segmental member 36 which is mounted to swing about a 110 stud 37 in the frame of the machine. The member 36 is oscillated by an eccentric rod 38, one end of which engages an eccentric 39 on the main shaft 28. The eccentric rod is connected to the member 36 by connections indicated at 40. The teeth 34 of the needle holder slide laterally with relation to those of the member 36 when the carriage 24 is moved laterally; but the teeth have sufficient width to maintain operative engagement. 120

The member 18 is formed with a shank 41 (see Figs. 7, 8 and 9) which occupies a socket in a holder 42. A setscrew 43, threaded in the holder, engages the shank to secure 125 the same, one side of the shank being flattened, as shown by Fig. 8, to prevent turning thereof. The holder 42 is fitted to slide longitudinally of the shank 41 in a depending portion 24' of the carriage 24, the por- 130

tion 24' being formed with a recess 44 for the reception of the holder. (See Figs. 8 and 13.)

The holder is engaged by a pin 45 affixed at the lower end of a lever 46, the carriage portion 24 and the holder 42 being slotted for the reception of the pin, as shown by Figs. 7, 8 and 9. The lever 46 (see Fig. 10) is mounted upon a fulcrum stud 47 in the frame of the machine, and its upper end is subject to the tension of a spring 48 by which the holder is normally advanced toward the work. The lever 46 is provided with a roll 49 which is held in engagement with a cam 50 on the shaft 28. The cam effects the retraction of the holder at the desired time. When the feed carriage is moved backward or forward, the holder slides along the pin 45.

The channel member 17, which co-operates with the member 18 to clamp and feed the work, is affixed to a holder 51 (see Fig. 11), which holder is mounted in the carriage 24 so as to be movable about the needle axis and may be mounted upon the same stud 23 which carries the needle holder. The member 36 which operates the needle holder also serves to operate the holder 51 which carries the channel member 17. For this purpose the holder 51 is provided with an arm 52, at the free end of which is a stud 53. This stud extends through a roller or bushing 54 (see Fig. 15) which occupies a cam slot 55 in the member 36. The roller 54 is provided with flanges, such as that indicated at 56, by which it is retained in co-operative relation with the member 36, the stud 53 being adapted to slide back and forth through the roller when the feed carriage 24 is moved. The arm 52 is braced by a plate 57 affixed to the carriage 24. The cam surfaces on the member 36 cause the channel member to move toward the member 18 when the needle is advancing toward the work, and to recede from the member 18 when the needle is receding from the work. The action of the channel member is positive, but the coaction of the member 18 is yielding, being caused by the spring 48. The member 18 is held forward at all times except during the return stroke of the carriage 24 preparatory to feeding the work.

The pointed member 20, by which the work is held stationary during the brief interval when the members 17 and 18 are released from the work, is held forward by the spring 58 (see Fig. 11) connected with a carrier 59 to which the holder 21 is affixed. The carrier 59 is mounted upon parallel oscillatory links 60 and 61. The link 60 is affixed to one end of a rock shaft 62 mounted in bearings at the rear of the frame, and the link 61 is mounted upon a pivot stud 63 near the front of the frame. The rock shaft 62 is provided with a friction drum 64 (see

Figs. 16, 17 and 22) by which the pointed work-engaging member is locked in its forward position and by which it is retracted prior to the feeding of the work. This mechanism is in all respects similar to that described in said Letters Patent 1,125,038. A pin 65 is used to fix the drum 64 on the rock shaft. An annular groove 66, formed in one side of the drum, is occupied by a split ring 67. The split ring normally tends to free itself from the friction drum, but its ends are adapted to be forced apart so as to expand it against the outer flange of the drum.

Figs. 18 and 22 illustrate a member by which the split ring is expanded. This member, hereinafter termed a controller, is indicated at 68. It is provided with a square boss 69 and with parallel fingers 70 having confronting parallel faces adapted to receive a sliding block 71. The block receives a pin 72 affixed to a bell-crank lever 73. The square boss 69 occupies the space in the groove 66 between the ends of the split ring. (See Fig. 17). The bell crank 73 is mounted upon a fulcrum stud 74 and is provided with a cam roll 75 which co-operates with a cam 76 (see Fig. 10) on the main shaft 28. The action of the bell crank, due to the cam, throws the controller 68 first in one direction and then in the other, causing the square boss 69 to first expand the split ring 67 and then to turn the same about the axis of the rock shaft 62. Yielding stops 77 and 78 are arranged in the path of the controller 68 and are adapted to be engaged by the lower end of the controller to insure the expanding and releasing of the split ring. The stop 77 is pivotally mounted on a stud 79, and it is held against a setscrew 80 by a spring 81. The stop 78 is pivotally mounted on a stud 82 and is held against an abutment 83 by a spring 84. The stop 77 effects the release of the split ring so that the pointed member 20 may be held in operative position by the spring 58. The stop 78 insures the expansion of the split ring so that the pointed member may be retracted by the action of the bell crank 73.

The main work rest or bunter 19 carries gear teeth in the form of a rack, indicated at 85 in Fig. 10. This rack co-operates with a pinion 86 (see Figs. 16 and 22) formed upon a sleeve 87. The sleeve is loosely mounted on the rock shaft 62. A clock spring 88 tends to hold the work rest toward the work, one end of the spring being attached to the sleeve, as shown by Fig. 16, and the other end being attached to any suitable fixture or portion of the frame.

A friction drum 89, similar to the drum 64, is fixed to the sleeve 87. The drum 89 is likewise formed with an annular groove and contains a split ring 67' like that described. The controller therefor is indicated

at 90. (See Figs. 21 and 22). This controller has a square boss 91 for expanding the split ring, and has a circular boss 92 which is surrounded by a plate or link 93. 5 The link is also engaged with a stationary stud 94 by which the square boss 91 is prevented from moving about the axis of the rock shaft 62.

The member 90 has a finger 95 which is 10 periodically engaged and disengaged by a lever 96, the finger 95 curving about the stud 72 so as to permit the latter to operate without interference.

The lever 96 is mounted upon the stud 74 15 and is moved in one direction by a spring 97.

A follower 98 is interposed between the spring and the lever 96, the spring and follower being contained in a socket formed in a boss 99 on the frame. (See Fig. 10). 20 By a cam hereinafter mentioned, the lower end of the lever 96 is periodically retracted from the finger 95 to permit the split ring 67' to release the drum 89; but when the lever is not so retracted, the action of the 25 spring 97 serves to turn the member 90 about the axis of the bosses 91 and 92 to expand the split ring and lock the drum 89, the drum being held against rotation by the link 93. In this way the work rest 19 is 30 normally locked in operative position.

A cam 100 (see Fig. 10) serves to retract the lever 96 to effect the release of the friction drum 89. For this purpose the lever 96 is provided with an ear 101 which stands 35 in the path of the cam 100 and by which the lever is retracted against the force of the spring 97.

The foregoing explanation of the manner in which the members 19 and 20 are locked 40 and released relates to the operation when the machine is being driven forward to sew. By a somewhat similar operation the members 19 and 20 may be released at the completion of the sewing operation and the 45 member 20 may be retracted, all of which is effected by manually turning the main shaft 28 in the reverse direction through a fraction of a revolution. For this reason the pivot stud 74 which carries the levers 50 73 and 96 is mounted in a movable hanger 102. (See Figs. 10 and 20). The hanger is secured to the frame by a pivot stud 103. One arm of the hanger carries a pawl 104 which is held by a spring 105 against a disk 55 106 on the shaft 28, said disk having a single ratchet tooth 107. The tension of the spring 105 also positions the hanger, the latter being provided with a nose 108 which is normally held against the frame, as 60 shown by Fig. 10. When the power shaft is being driven forwardly, as indicated by the arrow in Fig. 10, the hanger 102 remains motionless, but when at the completion of a sewing operation the shaft is rotated in 65 the reverse direction, the tooth 107 abuts

against the end of the pawl 104 and rocks the hanger 102 against the tension of the spring 105. This movement of the hanger carries the pivot stud 74 toward the front of the machine, and in this way the levers 73, 70 and 96 are actuated to release the split rings in the drums 64 and 89. At the same time, a finger 108' at the lower end of the hanger 102 engages an ear 109 on the periphery of the drum 64, thus turning the drum to retract the member 20 from the work. The hanger 102 carries a pin 110 which engages a lever 111 forming a part of thread clamping mechanism indicated generally at 112. The effect upon the thread-clamping mechanism is to release the tension upon the thread 113 which supplies the needle. The tooth 107 by which the thread is released, by which the main work rest is unlocked and by which the pointed member 20 is retracted, is so positioned with relation to the other cams as to act when the member 18 is retracted and when the needle and channel member are retracted. All of the instrumentalities which act upon the work are thus retracted at the same time, so that the work may be freely inserted and removed. 85

I claim:

1. In a shoe-sewing machine, a curved hooked needle, an oscillatory holder therefor, a laterally movable carriage for said holder, said holder being mounted on a pivot stud in said carriage, means for operating said holder, means for operating said carriage to feed the work, a work-engaging member mounted in said carriage so as to be movable toward and from the work, said member being adapted to bear against the outer side of the between substance, yielding means for causing said member to brace the between substance against the stress of the needle, and means adapted to engage the outer side of the between substance and brace the same rigidly. 95 100 105

2. In a shoe-sewing machine, a curved hooked needle, an oscillatory holder therefor, a laterally movable carriage for said holder, said holder being mounted on a pivot stud in said carriage, means for operating said holder, means for operating said carriage to feed the work, a work-engaging member mounted in said carriage so as to be movable toward and from the work, said member having two separated fingers adapted to bear against the outer side of the between substance at the right and left respectively of the needle, and means for operating said member to brace the between substance against the stress of the needle, and to retract said member from the work. 110 115 120 125

3. In a shoe-sewing machine, stitch-forming mechanism including a needle, a movable back rest arranged to coact with yielding pressure with the outer side of the between substance in advance of the needle, 130

means arranged to lock said back rest intermittently in work-engaging position, means arranged to grip the between substance between said back rest and the needle, 5 and means arranged to move said gripping means to feed the work.

4. In a shoe-sewing machine, an oscillatory hooked needle, a member for engaging the outer side of the between substance, said 10 member being movable toward and from the work, means for holding said member rigidly in work-engaging position to resist stress upon the work, said means being adapted to periodically release said member, 15 and two co-operative members adapted to engage respectively the inner side and the outer side of the between substance, means for causing said co-operative members to clamp and release the between substance, 20 and means for moving said co-operative members laterally to feed the work.

5. In a shoe-sewing machine, stitch-forming mechanism, means arranged to tuck the upper into the angle of the shoulder and 25 feather of the insole, and means arranged to grip the between substance while the upper is held against the shoulder of the insole by said tucking means, said gripping means being laterally movable while gripping, to 30 feed the work.

6. In a shoe-sewing machine, stitch-forming mechanism including a needle and needle-operating means, means arranged to tuck the upper into the angle of the shoulder and feather of the insole while the needle is retracted, and means arranged to 35 grip the between substance while the upper is held against the shoulder of the insole by said tucking means and before the needle enters the between substance, said gripping means being movable laterally while gripping, to feed the work.

7. In a shoe-sewing machine, stitch-forming mechanism including a needle and operating means therefor, means arranged to tuck the upper into the angle of the shoulder and feather of the insole in advance of the 45 needle, and means arranged to grip the between substance between said tucking means and the needle while the upper is held against the shoulder of the insole by said tucking means, and before the needle enters the between substance, said gripping means being movable laterally while gripping, to 50 feed the work.

8. In a shoe-sewing machine, stitch-forming mechanism including a needle and operating means therefor, work-feeding means including coacting gripping members arranged to grip the between substance and move laterally while gripping, and means arranged to tuck the upper into the angle of the shoulder and feather of the insole in advance of the needle after each feed movement and before said gripping members re- 55

lax their hold upon the between substance, said gripping members being arranged to take a fresh hold upon the between substance between said tucking means and the needle while the upper is held against the shoulder of the insole by said tucking means. 70

9. In a shoe-sewing machine, stitch-forming mechanism including a needle and operating means therefor, two work-engaging members arranged respectively at opposite 75 sides of the needle to brace the work against the stress of the needle, the one of said members which engages the work in advance of the needle being formed and arranged to tuck the upper into the angle of the shoulder and feather of the insole, and means arranged to grip the between substance between said tucking member and the needle while said tucking member is holding the upper in said angle, said gripping means being movable laterally while gripping, to 80 feed the work.

10. In a shoe-sewing machine, means for feeding the work step by step, a work-engaging member having a point arranged to pierce the stitch-receiving flange of the upper, to tuck said flange into the angle of the insole, and means for moving said member to and from coactive engagement as aforesaid to steady the work between the 95 feeding steps.

11. A work-engaging member having a point for piercing the stitch-receiving flange of the upper, and having a relatively broad surface for bearing upon the offset portion 100 which connects said flange and the body of the upper, and operating means for causing said member to coact with the said flange and offset portion between feeding steps to steady the work and tuck the upper into the 105 angle of the insole.

12. In a shoe-sewing machine, laterally movable means for feeding the work step by step, operating means therefor, a work-engaging member having a flat under surface 110 and a pointed end, said member being movable downwardly toward the work and upwardly from the work so as to place said flat surface upon the feather of the sole and to cause said pointed end to pierce the outer 115 side of the between substance, and operating means for causing said work-engaging member to engage the work at the end of each feeding movement and to release the work prior to the beginning of each feeding 120 movement.

13. In a shoe-sewing machine, an oscillatory hooked needle, two movable members adapted to engage the outer side of the between substance at the right and left respectively of the needle, means for causing one of said members to act upon the work with yielding force, means for rigidly holding the other of said members in work-engaging position, a member adapted to en- 125 130

gage the inner side of the between substance in coöperative relation to the yielding member to clamp the between substance, and means for imparting lateral feeding movement to the coöperative clamping members, said holding means being adapted to release the member which it holds to free the work for feeding.

14. In a shoe-sewing machine, an oscillatory hooked needle, coöperative clamping members for engaging respectively the inner side and outer side of the between substance, means for causing the outer member to act with yielding force, the inner member being rigid, means for moving said clamping members laterally to feed the work, means for retracting the outer member from the work prior to return lateral movement, and a member adapted to rigidly engage the outer side of the between substance when said yielding member is retracted to hold the work stationary.

15. In a shoe-sewing machine, two members adapted to engage respectively the inner side and the outer side of the between substance, the inner one of said members being movable laterally for feeding, a second member for engaging the outer side of the between substance, said second member being movable laterally and toward and from said inner member to coöperate with the inner member to clamp and feed the work, the first of said outer members being movable toward and from the work, and means for causing said first member to recede from the work preparatory to feeding movement, and to return to and remain in work-engaging position to hold the work stationary throughout the period when said coöperative clamping members are open.

16. In an inseam-sewing machine, means arranged to feed the work step by step, a work-engaging member having one or more teeth arranged to indent the outer side of the stitch-receiving flange of a shoe upper, means arranged to move said work-engaging member against said flange with yielding force, means arranged to lock said work-engaging member intermittently against retractive movement, and means arranged to

retract said work-engaging member to free the work for feeding.

17. In a shoe-sewing machine, stitch-forming mechanism including a needle and operating means therefor, said needle being movable laterally to feed the work, means arranged to alternately engage and disengage the work to tuck the upper into the angle of the shoulder and feather of the insole in advance of the needle, and means arranged to alternately engage and disengage the work to press the upper against said shoulder between said tucking means and the needle, said pressing means being movable laterally with the needle while pressing the upper as aforesaid, said tucking means and said pressing means being arranged to keep the upper pressed continuously against said shoulder.

18. In a shoe-sewing machine, stitch-forming mechanism including a needle, means arranged to grip the between substance in advance of the needle, means arranged to move said gripping means to feed the work, a back rest arranged to coact with the outer side of the between substance in advance of the needle, and means arranged to move said back rest intermittently to and from the between substance to hold the work stationary between feeding movements and to free the work for feeding.

19. In a shoe-sewing machine, stitch-forming mechanism including a needle, means arranged to grip the between substance in advance of the needle, means arranged to move said gripping means to feed the work, a back rest arranged to coact with the outer side of the between substance in advance of said gripping means, and means arranged to move said back rest intermittently to and from the between substance to hold the work stationary between feeding movements and to free the work for feeding.

In testimony whereof I have affixed my signature, in presence of two witnesses.

HARRIE A. BALLARD.

Witnesses:

CHARLES S. JOHNSON,
M. E. CAPEN.
